SHIP'S OVERSEDE ELEVATOR

John Lamb, Great St. Helen's, London, England, assignor to Shell Development Company, New York, N. Y., a corporation of Delaware

Application July 22, 1954, Serial No. 445,079

Claims priority, application Great Britain July 27, 1953

1 Claim. (Cl. 187—6)

This invention relates to a ship's overside elevator, hoist, or lift, and to a ship provided with such a device whereby access to or from a ship's deck can be provided without the usual companion ladder or gangway; the invention further relates to a control for such an elevator. The elevator car or hoist, hereinafter referred to as "car" for the sake of brevity, is of the type provided with running wheels which, during the operation of the car, are in contact with the ship's side. A ship's overside elevator has certain advantages, for example, it requires much less deck space when stowed, over methods of access such as a gangway or companion ladder.

Elevators or hoists for providing access to ships' decks have been previously proposed, and in these previous proposals the problem of keeping the running wheels of the car in a predetermined position relative to the side of the ship has been solved by providing rigid guides for these wheels down the side of the ship. Such guides are disadvantageous since, if permanently in position, they increase the resistance of the hull to movement through the water and they are liable to damage by crushing against a quayside; if only temporarily in position, their rigging and securing in position are inconveniently laborious.

It is an object to provide a ship's overside elevator that has running wheels adapted to run against the ship's side or hull without special guides, while being urged against the ship's side so that there will be no tendency for the car to sway.

A further object is to provide an improved elevator car comprising a chassis carrying the running wheels that bear against the ship's hull, a support structure for attachment by a suspension cable, a car body adapted for occupancy by passengers and carried, e. g., in fixed relation to the support structure or to the chassis, and a linkage interconnecting the chassis and the said support structure and arranged to increase the distance between said support structure and the chassis, so that the support structure is pushed away from the hull of the ship to a distance that increases as the car descends, whereby the said suspension cable always exerts a horizontal component urging the running wheels against the ship's side.

Still another object is to provide an improved control device whereby the movement of the car can be controlled by the occupants of the car and/or controlled automatically by the approach of the car to some obstruction, such as a solid body or a liquid body.

In summary, according to the present invention there is provided a ship having an overside elevator car suspended along side the hull by suspension cable means including an inclined, primary cable, and having at least three running wheels mounted on one side of the car on a chassis in a pattern corresponding to apices of a polygon, e. g., a triangle or rectangle, whereby the wheels determine the inclination of the chassis to the hull upon contact with the ship's side, the car having a movable support structure for attachment to said inclined cable, a variable-length linkage interconnecting said support struc-

2

ture and the chassis, and a mechanism actuated by the suspension cable means for increasing the effective length of said linkage as the car descends, so that the part of the inclined cable between said support structure and the point of support on the ship (e. g., a pulley, drum or the like) is maintained at an inclination to the vertical, with the upper end of such part inboard with respect to the lower end, so that the said cable provides a component of tension that urges the car in an inboard direction and presses the running wheels against the ship's side. By this arrangement the car can be operated without guide tracks on the side of the ship.

In the preferred embodiment to be described the car includes an enclosed body for passengers and the said car body is movable with respect to the chassis, the said support structure being mounted in fixed relation to the car body. Moreover, the said support structure comprises a pair of pulleys, mounted coaxially on opposite sides of the car body, and these pulleys, by their rotation, drive the mechanism for altering the length of the said linkage. Finally, the said linkage comprises an articulated strut that is retractable and foldable within a housing on the car and is forced outwards upon rotation of the said pulley. However, the invention in its broadest aspects is not limited to any of these three features, the only necessary displacement outward from the hull being that of the said support structure. One may power the linkage by other cable means, e. g., by a secondary cable connected to the chassis as described below other suitable linkage arrangements may be employed. Whatever the type of linkage used, it is preferably duplicated so that there is one linkage on each side of the car. The advantages of the preferred arrangement are that it provides a car that is reliable in its operation and requires the minimum of stowage space when out of use.

The outward movement of the movable support structure from the chassis, which structure is the point at which the primary cable acts on the car, involves a shift of the center of gravity of the car as a whole and this could be counteracted by balance weights in a car having only a single suspension cable (or a pair of primary cables connected to the said support structure); however, it was found simpler and more dependable to provide a secondary cable or cables which acts on the car at a point fixed in relation to the running wheels, e. g., connected to the chassis or to a suspension structure secured above the chassis, in addition to the primary cable or cables connected to the movable support structure, and to locate the points of action of the cables so that the center of gravity of the car lies within the polygon having said points of action as apices. As was noted above, either the primary or the secondary cable may pass over a pulley and actuate the linkage.

The linkage according to the invention is preferably constituted by an articulated strut comprising a plurality of links that are substantially rectangular in profile and are connected by articulated joints of a suitable type, such as pivot pins situated at the ends of the longer sides of the links. Such a linkage can flex freely in the direction causing the shorter sides of adjacent links to separate, but any tendency to flex in the opposite direction is resisted by abutment of the ends of the links near the said shorter sides. Such a linkage, if guided or held in an arc with the said longer sides of the links on the convex or outer side of the arc, is able to resist compressive stress without danger of buckling, and assumes the shape of a shallow arc with the said shorter sides of the links pressed against each other and the longer sides of the links in tension.

A linkage of this type is advantageous because it can be folded and retracted in such a manner that it forms no appreciable projection from the car and, therefore, facilitates stowage of the car on deck. By providing teeth on

the links the linkage becomes a rack that can be driven by a pinion.

In the apparatus according to the invention, the wheels run on the side of the ship itself, insofar as this is not prevented by discontinuities in the hull, without the interposition of permanent or temporary guides. If, however, there are one or more discontinuities in the path of travel of the car due, for example, to intervening open decks or to the location of the ship's superstructure inboard from the hull line, such discontinuities are bridged by tracks which may take the form of guides, affixed flush to the ship's side for supporting the car wheels as they pass over the said discontinuities. It is preferred to provide the wheels with tires of rubber or the like as these not only promote smoothness of running but also obviate damage to the paint on the ship's side and prevent sparking, which may be dangerous when inflammable liquids are being handled on or near the ship.

The car, when not in use, is preferably stowed on the ship's deck. The car may be launched from the deck by any method or apparatus, usually from a deck other than that used to enter the car. The drawings hereof will show elements of a launching apparatus that is described more completely and claimed in my copending application Serial No. 445,977, filed concurrently herewith.

The pulley or drum from which the cable is suspended may be fixed directly on the horizontal shaft of a winch motor, but it is generally preferred to locate the winch on one of the ship's decks, usually that next above the deck to and from which the car operates. In that case, pulleys are provided for guiding the cable from the suspending pulley to the winch.

The present invention also includes the provision of means whereby the operation of the car may be controlled by the occupants thereof and also means whereby the downward travel of the car can be controlled automatically. This means includes a lanyard suspended from the ship and there connected to a cut-off device for controlling the operation of the winch and cable brake, the movement of the lanyard relative to the car being normally free but capable of being checked by a locking device that can be operated manually. The system further includes a sensing or stop member capable of movement in relation to the car and connected to actuate the said locking device by such movement upon engaging an obstruction, such as a solid surface or a water surface.

Having thus described the invention generally, reference is made to the accompanying drawings which form a part of this specification and show, by way of example, one preferred embodiment, in which:

Figure 1 is a side elevation of an elevator car according to the invention in its operative position but shown above the access deck, against the launching platform of an oil tanker, parts of the tanker being shown in section, the condition of the car in relation to the ship when at the access deck for receiving passengers being shown in chain lines;

Figure 2 is a front elevation of the car in Figure 1, viewed from the outboard direction, parts of the tanker ship being shown in side elevation;

Figure 3 is a front elevation of the car on an enlarged scale viewed from the outboard direction, parts of the linkage and the housing therefor being in section and the housing being omitted from the left side for clarity;

Figure 4 is a side elevation of the car with certain detail not shown in Figure 1, on the same scale as Figure 3;

Figure 4a is a side elevation of a part of the linkage shown in Figure 4;

Figure 5 is a diagrammatic view, on a reduced scale, showing the car in relation to a ship;

Figure 6 is a diagrammatic side elevation of the car showing a preferred arrangement of the lanyard and control system;

Figure 7 is an enlarged sectional elevation of the locking device used in the control system; and

Figure 8 is a sectional elevation of a drum at the bottom of the car body for accommodating the lanyard.

Figures 1, 2 and 5 of the drawing show a part of a tanker ship having open decks A and B, of which the former is used to stow and launch the elevator car 1 and for the winches (not shown) and the latter is used as the point of ingress and egress, being the highest deck to which the car moves in normal operation. The car is suspended by suspension cables that include inclined, primary cables 2, situated one on each side of the car and having their fixed ends anchored to the ship, e. g., at anchorages 3 carried on a tiltable launching platform 4; these cables pass beneath a pair of pulley wheels 9, mounted coaxially on opposite sides of the car, and thence over and under idler pulleys 6 and 7 carried by the ship, e. g., on a frame 8 that is rigidly mounted. The pulley wheels, together with the mounting therefor, to be described, constitute the movable support structure by which the car is supported by the inclined suspension cable.

As is shown more clearly in the chain line position in Figure 1, the elevator car 1 comprises an open top body adapted to accommodate passengers, and a chassis 12 on 11, mounted in fixed relation to the pulley wheels 9 and which are mounted four running wheels 13 arranged at 30 two levels, the car body and chassis being interconnected by a variable-length linkage 27. As will be appreciated from the description set out below, the car body 11 may move in relation to the chassis 12 to vary the horizontal interval; this is evident from a comparison of the solid and chain line views of the car in Figures 1 and 5. It may be noted that the expression "movable support structure" denotes that the parts engaged by the inclined suspension cables, e. g., the outboard rims of the pulley wheels 9, are movable in inboard and outboard directions relatively to the chassis. The body 11 may have a panel 11a that is hinged at 11b (Fig. 3) and can be swung onto the deck B to serve as a gang plank as shown in chain lines in Figures 1. The running wheels 13 engage the ship's side 39; at places where the ship's hull is discontinuous or above the hull, e. g., at open decks and opposite the superstructure 40 of the ship that is set inboard from the hull line, tracks 41 are provided to provide trackways for the wheels 13, said tracks being in alignment with the ship's side 39. These tracks may have flanges, as shown, to guide the wheels. A secondary suspension cable 14 is attached to the chassis 12 approximately in the plane of the axles of the wheels 13, as shown; this cable passes over and under pulleys 6a and 7a, mounted coaxially with the pulleys 6 and 7.

By arranging for the primary cables 2 to pass over a winch drum or drums having twice the diameter of the drum over which the secondary cable 14 passes, a single winch may be arranged to operate the car. This arrangement and the control of this winch, apart from the control lanyard and cut-off device disclosed below, form no part of the present invention and do not require illustration or further description herein.

The launching platform 4 is pivoted on pins 5 carried in the frame 8 for rotation of the platform on a horizontal axis situated near the ship's side somewhat above the bottom of the platform, so that the latter, when in the raised position shown, has the outboard face thereof substantially in alignment with the ship's side 39. The platform is normally locked in the raised position by a latch 10, but may be swung inboard to a lower position with an end thereof on the deck A. The car 1, on its side 76 with the wheels 13 lowermost, can then be rolled on the

deck and onto the lowered launching platform. The platform and car carry securing means (not shown) for fastening the car to the platform so as to support the car while the platform is swung to the raised position and while the suspension cables are attached. The platform and securing means do not form a part of the instant invention and do not require further description herein.

Turning now to Figure 3, the chassis 12 is formed as a framework having two upright, laterally spaced tubular members 15, which are rigidly secured to a lower, transverse member 16, and an extensible section having a pair of rods 17 mounted for sliding movement within the members 15 and united at the top by a transverse beam 18, to which the secondary suspension cable 14 is attached by a shackle 19. The lower ends of the rods have enlarged heads 17a that limit the outward sliding movement by engagement with caps 15a that are fixed to the upper extremities of the tubular members. The chassis has, therefore, a telescopic unit at each side thereof. The telescopic nature of the chassis 12 is primarily of importance in permitting the overall dimensions of the car to be reduced for convenient stowage of the car on deck. The beam 18 may further carry a caster wheel 20 which is mounted at the midpoint of the beam by a screw mechanism that is extended and retracted by a handwheel 21. The caster is shown in extended position in Figure 1 and retracted in Figure 4. When the slides 17 are retracted within the members 15 and the caster wheel is extended, the car may be moved on its side about the deck with the running wheels nearest the caster wheel raised from the deck; by operating the handwheel 21 the caster wheel can be retracted to permit all running wheels to engage the deck or ship's side. The caster wheel is primarily of importance for rolling the car on its side during launching and stowage. The caster wheel and the telescopic nature of the chassis are not essential to the present invention. It is only to be noted that the point of attachment of the cable 14 should be as high as feasible above the center of gravity of the car. Auxiliary wheels 22 may be mounted on spindles at the ends of the beam 18 to prevent the beams from scuffing the ship's side.

Each pulley wheel 9 is mounted on and keyed to a separate stub shaft 23 carried in bearings 24 and 25, which are mounted in fixed relation to the car body 11. These stub shafts are advantageously situated on a common axis that lies outboard from the center of gravity of the car body, as shown. These pulley wheels rotate as the car moves up and down and hence constitute cable-actuated rotatable drive elements for the variable-length linkage to be described. A spur gear or pinion 26 is fixed non-rotatably to each stub shaft 23 between the bearings 24 and 25 for rotation with the pulley wheel 9. Each spur gear 26 engages a separate articulated toothed rack that constitutes the variable-length linkage and is indicated generally by the reference 27, Figures 1, 3, 4, 4a and 5. Each of these linkages is guided as shown in Figure 3 by shoulders 28 and 29 formed on the shaft 23 and also by a horizontal plate 30 disposed in spaced relation beneath the shaft 23; it is further guided by rollers 31 and 32 mounted on the car body (Figure 4).

Each linkage 27 comprises a long, horizontal primary link 33 which is pivotally connected at 34 to a pair of bracket plates 12a that are fixed to the upright member 15 of the chassis, and also a plurality of shorter, secondary links 35 of substantially rectangular profiles, with one longitudinal side longer than the other. Each link has an articulated connection with its neighbor; thus, these links may be connected to one another and to the primary link by pivot pins 36 situated near the longer sides of the links. The shorter sides of the links carry teeth that mesh with the spur gear 26 and the ends of the links are adapted to abut one another at the shorter sides. The links are thereby able to pivot with respect to each other in the direction tending to separate the said shorter sides.

but folding in the opposite direction is prevented after the said ends move into abutment. The car carries a convolute channel or housing which includes inner and outer guide plates 37 and 38 and may include straight traverses joined by arcs, as shown. The housing is shaped to accommodate the linkage in the folded and retracted position shown in Figure 4. The upper leg of the housing is open towards the chassis to permit the primary link to protrude. A similar housing is provided at the opposite side of the car for the other linkage. It will be noted that by folding and retracting within the convolute channels the linkages 27 form no appreciable projection from the sides of the car. Moreover, the projection formed toward the outboard side (at the right-hand side of Figure 4) by the housing extends in an upward direction when the car is stowed on deck with the running wheels downward, and hence occupies no extra deck space; this projection is small and so does not prevent stowage between decks.

As the elevator car descends from the uppermost position shown in full lines in Figures 1 and 5, the pulley wheels 9 rotated and, with them, the spur gears 26. The engagement of the latter with the teeth on the linkages 27 causes the axes of the pulley wheels 9 to move outboard from the chassis 12, thereby increasing the effective length of the linkage. It is evident that the movable support structure or point of action of the inclined cable 2 is thereby moved outboard, to the right-hand as viewed in Figure 4. The car body 11, on which the pulley wheels are mounted, is likewise pushed outboard. After the primary links have passed the pinion 26 they are followed by the adjacent and subsequent secondary links 35. While the linkage is thus projected from the housing on the car body, the rollers 31 and 32 insure that the inboard portion of the linkage (nearer the chassis 12) is urged downward, this action being promoted by the location of the cable support structure or pulley wheels 9 outboard from the center of gravity of the car body, as shown. The resulting slight upward movement of the outboard end of each linkage biases the linkages to form rigid shallow arcs that are downwardly convex; they thereby form strut members between the pivotal connections 34 and the shafts of the pulley wheels. The slight downward arc insures that the struts are stable against buckling. The intermediate part of the strut cannot move downward in relation to the ends of the strut because this would require a folding action in the direction prevented by the abutments between the ends of the links.

In this manner the body 11 of the car moves away from the ship's side 39 (or bridging channels 41) and maintains the inclination to the vertical of the primary suspension cables 2, whereby there is provided an adequate component of cable tension to urge the running wheels 13 into contact with the ship's side (or channels).

It may be noted, by way of example, that the outer rims of the pulleys 9 should move to a position approximately 9 feet, 6 inches, away from the side of the ship when the elevator car has travelled 30 feet down from its uppermost position, while at the uppermost position of the car this outboard distance may be approximately 2 feet, 9 inches.

When the car is raised the pulley wheels 9 and pinions 26 rotate in the opposite directions, retracting the linkages 27 and decreasing the outboard distance of the pulley wheels 9 from the ship's side.

It will be appreciated from the foregoing that the linkages 27 and the operating pulley wheels with their pinions 26, which constitute the cable-actuated rotatable drive element and the mechanism for operating the linkages, respectively, could equally well be mounted on the chassis 12, with pivotal connections of the outboard ends of the linkages to the movable support structure and car body 11 by a simple reversal of parts. In this case the movable support structure could take the form of pulleys or simply of shackles for engagement with the

inclined cables 2, and a housing for retraction and folding of the linkage can be mounted on the chassis.

The linkages 27 described above have the advantage that the outward movement of the body 11 is directly proportional to the distance of descent, so that when the ship's side is of uniform slope, the inclination to the vertical of the primary cables 2 is maintained substantially constant. This proportionality of movement is not, however, essential and other linkages which do not provide such proportionality to a high degree may be used. Thus, the rotation of the pulleys 9 may be used to turn an arm having a pivotal connection with a second arm which is, in turn, pivotally connected to the chassis 12.

Considering next the control system, the car is provided with a relatively movable stop member situated below the car, and with a lanyard arranged to operate a movable cut-off member on the ship which controls the operation of the winch or the like used to lower the car, this lanyard passing through a releasable locking device on the car and having one end secured to the ship, the arrangement being such that, when the car is moving normally, the locking device is open and the car moves in relation to the lanyard passing through the locking device; and also that upon the occurrence of relative movement between the stop member and the car, the locking device is actuated to lock the lanyard in relation to the car so that, with further downward movement of the car, the cut-off member is operated to stop the car.

The free end of the lanyard, that is to say, the end not attached to the ship, is preferably wound upon a take-up device such as a spring-controlled drum which may be situated either on the car or on the ship; such a device can, however, be omitted by permitting the free end of the lanyard to hang beneath the car.

The control system is illustrated in Figures 6-8, wherein the parts of the car are indicated diagrammatically. The car is suspended and operated as described above in connection with Figures 1-4 and is provided additionally with a lanyard 50 and 50a, a releasable locking device 52 through which this lanyard passes, and a stop member 53 connected to the releasable locking device 52 by a line 70; all but the last two parts are omitted from Figures 1-5.

The lanyard is, for convenience in rigging, made of two parts joined by a coupling link 51. The upper part 50 has the end thereof secured to the ship's structure by an anchorage 54 and passes thence under a lower pulley 55, over an upper pulley 56, and downward toward the car. The lower part 50a passes through the releasable locking device 52 on the car, under the idler pulley 57 mounted on the car, and onto a spring-controlled drum 58 mounted beneath the car for rotation on a vertical axis. The pulley 56 is carried by a pivoted cut-off member or arm 59 that is urged upwardly by a spring 60. This arm operates a combined switch and brake (not shown) on the winch which operates the car and is so arranged that downward movement of the arm immediately stops the winch. The pulley 55 is carried by a weight 61 which may move up and down in guides 62, this arrangement being provided to prevent damage to the arm 59 or lanyard. Such damage could otherwise result upon continued downward movement of the part of the lanyard that is at the car after the arm 59 has moved to its lowermost position.

The releasable locking device 52 comprises a toothed segment 63, an abutment plate 64 and a leaf spring 65. The spring urges the segment in a clockwise direction, as viewed in Figure 7. The lanyard 50a passes through fair leads 66 and 67 in close proximity to the abutment plate 64. The segment has serrations 63a that are situated at progressively increasing distances from the axis of the pivot shaft 68 on which the sector is pivoted, whereby a clockwise movement of the segment tends to press the lanyard against the abutment plate 64. The arrangement is such that, when the lanyard is moving

upwardly in relation to the locking device as shown in Figure 7, and is engaged by the toothed segment 63, it will tend to rotate this segment further in the clockwise direction, thus compressing and holding the lanyard between the serrations 63a and the abutment plate 64. A handle 69 is fixed to the segment 63 so that the releasable locking device may be manually operated by the occupants of the car if desired.

The line 70 is attached at one end to the segment 63 at an eye 71 and at the other end to the stop member 53, and passes over an idler pulley 72 carried by the car body 11. The weight of the member 53 is sufficient to overcome the force of the spring 65, so that the line 70 normally holds the segment 63 out of contact with the lanyard. Moreover, the stop member 53 is preferably buoyant to float on water.

As is shown in Figure 8, the bottom 31 of the car body has a plurality of dependent studs 32 by which it is supported a stationary barrel 33. A spindle 34 carried by and rotatable in relation to the barrel 33, carries the take-up drum 38. A spiral spring 73 is connected at one end thereof to the barrel 33 and at the other end to the hub of the drum 38. The tensions of the springs 60 and 73 and the mass of the weight 61 are so related to each other that the various components have substantially the relative positions shown in Figure 6 during the normal movement of the car; the arm 59 is shown in its raised position.

As the car descends, the free or slack portion of the lanyard 50a unwinds from the spring-controlled drum 58 and passes upwardly in relation to the car, through the releasable locking device 52. Conversely, when the car rises, the stated portion of the lanyard is wound upon the drum 58 by the action of the spring 73.

When the car descends and approaches an obstruction, the stop member 53 contacts, for example, the surface of the quayside 49 (Figure 5) while the car is still above it and thereby releases the tension in the line 70, whereupon the spring 65 acts upon the segment 63 to swing it into contact with the lanyard and lock the latter against the abutment plate 64. Continued descent of the car then causes the lanyard to draw the pulley 56 downwards and to rotate the arm 59 and operate the cut-off device to stop the winch, apply the brake and thereby stop the car. Since the stop member 53 is sufficiently buoyant to float on water, the action described above will occur also when the stop member encounters a water surface. The lanyard can be released or locked as desired by operation of the handle 69.

By way of example, the spring 65 may be such that its end exerts a force of 2 pounds against the segment 63 and the weight of the stop member 53 may then be about 3½ pounds.

I claim as my invention:

An overside ship elevator adapted to be supported by suspension cable means including inclined primary suspension cables and a secondary suspension cable and adapted to run on a ship's side without guides comprising: two vertical laterally spaced tubular chassis side members, a lower chassis traverse beam rigidly attached to said side members at their lower ends, a pair of rods mounted within said side members for slideable movement, an upper chassis traverse beam connecting said rods at their upper ends, running wheels attached to the ends of said upper and lower traverse beams, an elevator body connected to said chassis members on the outboard side thereof and movable outwardly from said chassis members, a variable length articulated beam interconnecting said elevator body and said chassis members to maintain said elevator body at a variable distance determined by the effective length of said articulated beam, primary suspension cables supporting said elevator body, a rotatable cable actuated drive means attached to said elevator body and engageable with said primary suspen-

sion cables for rotation thereby upon vertical movement of the elevator body, mechanism for increasing and decreasing the effective length of said articulated beam upon rotation of said cable actuated drive means, and a secondary suspension cable attached to said upper chassis traverse beam.
